CABINET OR THE LIKE

Warren C. Church, Hurt, Va., assignor to The Lane Company, Inc., Altavista, Va., a corporation of Virginia

Application December 5, 1958, Serial No. 53,662

Term of patent 14 years

(Cl. D33—19)

Fig. 1.

Fig. 2.

Figure 1 is a perspective view of a cabinet or the like embodying my new design; and

The essential features of the design are shown in the drawing in solid lines.

The back or rear of the cabinet or the like (not shown in the drawing) is plain and unornamented.

I claim:

The ornamental design for a cabinet or the like, as shown and described.
